UNITED STATES PATENT OFFICE.

WILLIAM T. TRUAX, OF BATTLE CREEK, MICHIGAN, ASSIGNOR TO UNITED STATES REGISTER COMPANY, OF BATTLE CREEK, MICHIGAN, A CORPORATION OF MICHIGAN.

REGISTER-FRONT FASTENER.

Application filed March 8, 1926. Serial No. 93,239.

This invention relates to register front fasteners. More particularly it belongs to that class of contrivances intended to secure the front or openwork plate or grating common to warm air registers in the frame or surrounding housing.

It is an object of this invention to produce a front fastener of simple character, readily and cheaply manufactured and applied, that may be quickly placed in position and as quickly removed in case of necessity, and which will be at all times held securely when in the frame, and which will present no unsightly protuberances, attachments or extensions, the whole front being left practically flush with the face of the frame. By reason of the simplicity of this invention no special skill or tools are called for to deposit the front in the frame and 20 to firmly and strongly fix it in place. It is a further object of this invention to provide a fastener of the nature mentioned which will comprise parts of special form, construction and arrangement particularly well adapted for the purposes intended.

In the accompanying drawings the special construction and disposition of the combined parts of this invention in its preferred form are illustrated. Fig. 1 is a front view of all the parts assembled. Fig. 2 is a vertical section on the broken line 2—2 of Fig. 1. Fig. 3 is a full size sectional view of the lower portion of the frame as set forth in Fig. 2, showing the particular form and arrangement of the depression in the face of the frame, and showing also the communicating slot. Fig. 4 is a side view partly sectional showing the screw fastener and the eccentric turning disk borne thereby on the inside of the edge of the lower portion of the front. Fig. 5 is a face view of the eccentric or locking disk.

Throughout the drawings and description the same number is used to refer to the same part.

Considering the drawings, the register frame 1 has a seat 2 formed to receive the openwork front. The upper part of the frame 1 has two separated slots 3 and 4, and those slots are located usually at the inner edge of a raised portion 5 of the frame

which forms the boundary outwardly of the seat 2 for the front. Two small tongues 7 and 8 are constructed to be introduced into the slots 3 and 4 to hold the upper edge of the front in place. It will be noted in Fig. 2 that the frame 1 has an opening 6.

The front or grating, which may be of any selected pattern as to its openwork, is designated by the reference number 9.

Passing through the lower edge of the front 9 will be noted the screws 10 and 11, each having a squared shank 12 as shown in Fig. 4, to fit the squared orifice in the fastener disk 13 as illustrated in Fig. 5. The shank of the screw 11 is headed as shown at 14 in Fig. 4 to hold the disk and shank together. It is thought to be clear from the drawings that the disk may be turned by inserting a screwdriver in the slot of the screw head.

Considering Fig. 3 it will be observed that the frame 1 has a depression 15 formed in the face thereof immediately above the raised portion 5. Usually the rear wall of the depression 15 is further depressed or countersunk as at 16 to receive the head 14 of the shank 12 of the turning screw-headed member 11, in order that all the parts may fit together and avoid projections which would tend to detract from the good appearance of the register as a whole. In Fig. 3 also it will be seen that the depression 15 has a communicating slot 17, and it is into this communicating slot that the disk 13 is turned to secure the front 9 in position in the frame 1.

In the operation of this invention, if by means of a screwdriver the screws 10 and 11 are so turned as to bring the disks into the depressions 15, the lower edge of the front may be raised from the seat 2, and the two small tongues 7 and 8 easily withdrawn. This may be very quickly and easily accomplished, and the replacement is made with like expedition. The sectional view, Fig. 2, shows that projections or extensions are reduced to a minimum.

Having now described this invention, and explained the mode of its operation, what I claim is:

The combination with a register frame, of

an open work front for the register, means for securing the upper edge of the said front in the frame in detachable relation, the lower portion of the said frame having spaced depressed portions forming recesses in the frame open at the bottom, and releasable securing devices carried by the said

front and constructed to be passed into the said depressions of the frame, the said devices having portions arranged to be turned 10 into engagement with the said open bottoms of the depressions.

In testimony whereof I affix my signature.

WILLIAM T. TRUAX.
